UNITED STATES PATENT OFFICE

PAUL L. GEER, OF BELLEVUE, PENNSYLVANIA, ASSIGNOR TO AMCO, INCORPORATED, OF PITTSBURGH, PENNSYLVANIA, A CORPORATION OF PENNSYLVANIA

APPARATUS FOR HEAT-TREATING

Application filed December 23, 1927. Serial No. 242,132.

My present invention relates to the heat-treating of metal and other articles wherein the articles are given successive heat-treatments in a plurality of heat chambers, furnaces or ovens.

Thus for instance in enameling metal articles, according to the present practice the article to be enameled is successively dipped, placed by hand in a drying oven and when dried is removed and placed in a burning furnace. After the first coat of enamel is baked, the article is removed, redipped, dried and again inserted into a burning furnace, and these steps of dipping, drying and burning are repeated until the desired enameling is effected.

It is evident that such practice requires repeated manual handling of the product during the enameling process, resulting in high labor and fuel costs and much loss of time. Again, owing to the importance of the human factor the product is lacking in uniformity and quality. Moreover a relatively excessive amount of factory space is

needed for the operation.

The object which I have in view is the provision of an improved enameling apparatus which will minimize the importance of the human factor, which will economize valuable factory space, which will reduce the time required for completing the operation, which will insure a product of high quality and of uniform character, and which will be attended by fuel economy.

The apparatus which I have invented consists of a unit comprising a plurality of drying ovens and burning furnaces alternately arranged end to end and with a continuous conveying floor extending through the ovens and furnaces.

The conveying floor may and preferably does comprise power-driven conveying rollers, and for this purpose I prefer to employ, at least within the high temperature furnaces the refractory arch type of roller which is the subject matter of Letters Patent of the United States No. 1,737,117, issued November 26, 1929.

The conveyer floor is exposed at the front of the first drying oven to permit the placing

of the dipped articles thereon, and a portion of the conveyer floor is exposed at the outlet ends of the burning furnaces to permit the product to be redipped and also to permit the product to be removed after the final coat is burned.

I provide novel means for maintaining the desired temperatures in the drying ovens and in maintaining the necessary atmospheric dryness therein.

Other novel features will appear from the following description.

In the accompanying drawing, wherein I have illustrated the best embodiment of the principles of my invention now known to me, Fig. 1 is a plan view; Fig. 2 is a side elevation, and Fig. 3 is a longitudinal section on enlarged scale and taken along the line 3-3 in Fig. 1.

Referring to the drawing, I provide a continuous conveying floor which may be, as shown, composed of the conveying rollers 1 which are power-rotated by any convenient means in a direction clockwise in Fig. 3.

2 represents a drying oven through which the conveying floor extends, the front end of the conveying floor being exposed so that the dipped articles may be placed thereon to be carried into and through the oven 2.

3 represents a burning furnace next in sequence to the drying oven 2 and through which the conveying floor also extends. The coat of enamel which has been dried in oven 2 is burned in furnace 3. The burning furnace is preferably of the muffle-type, as shown in Fig. 3.

In the rear of the furnace 3 a sufficient portion of the conveying floor is exposed to permit the articles to be removed for redipping. The redipped articles are replaced on said exposed portion of the conveying floor.

Next in sequence is a second drying oven 2 in which the second coat of enamel is dried and through which the conveying floor extends. Next in sequence is a second burning furnace 3 wherein the second coat is burned and through which the conveying floor extends. In the drawing I have illustrated three pairs of drying ovens and burning furnaces placed end to end, thus providing for

the drying and burning of three coats of enamel. In case additional coats are to be given to the product additional pairs of drying ovens and burning furnaces are provided to the desired number, the conveying floor extending continuously through the same.

5. The conveying floor is extended and exposed beyond the final burning furnace to permit the removal of the finished articles.

10. The ends of the burning furnaces are provided with adjustable end doors 4 to regulate the burning temperatures and to permit the travel of the articles into and out of the furnaces along the conveying floor.

15. The drying ovens are preferably heated by the waste gases from the burning furnaces.

The waste gases from the furnaces 3 are led to the recuperators 6 through the pipes 7 and air heated in said recuperators by said

20. waste gases is led from the recuperators through the pipe 8 and branch pipes 9 to the arcuate inverted U-shaped chambers 10 mounted on the roof arches of the drying chambers, the lower ends of said chambers

25. 10 communicating with the interior of the drying ovens and the heated air from the pipes 9 being admitted near one end of a chamber 10, thus causing an upward suction of the air from the drying oven and its circulation through the chamber 10 during which time it is dried and reheated by the air from the recuperator, so that when the air is returned into the interior of the oven at the other end of the chamber 10 it is

35. restored to its original heat and dryness. Thus I am able to maintain the uniform predetermined drying temperature in the drying chamber and to prevent the saturation or partial saturation of the atmosphere of the ovens by the moisture taken up from the

40. enameling fluid.

This arrangement of air reheating and drying chambers connected to the interior of the drying oven and which receive the heated air from the recuperators wherein the waste gases from the burning furnaces are employed for heating results in a very substantial economy in fuel.

45. It is evident that the use of my improved apparatus also accomplishes a very marked saving in labor costs and also in time. They also effect a substantial saving in plant space.

The product is also of a superior quality because of the diminution of the human

55. factor.

What I desire to claim is:

1. In enameling apparatus, the combination of a drying oven, a burning furnace, said oven and said furnace being separated by an intervening open space, a continuous conveyer extending through said oven, said open space and said furnace, a recuperator receiving the waste gases from the furnace, an air passage connected at two spaced apart

60. preheated air connection between the recuperator and said passage, the air being withdrawn from the drying oven at one end of the passage and dried and then reintroduced into the drying oven at the other end of the passage.

2. In enameling apparatus, the combination of a drying oven, a burning furnace, said oven and said furnace being separated by an intervening open space, a continuous conveyer extending through said oven, said open space and said furnace, a recuperator receiving the waste gases from the furnace, an air passage connected at both ends to said oven, and a preheated air connection from the recuperator to said passage, the air being withdrawn from the drying oven at one end of the passage and dried and then reintroduced into the drying oven at the other end of the passage.

3. In enameling apparatus, the combination of a drying oven, a burning furnace, said oven and said furnace being separated by an intervening open space, a continuous conveyer extending through said oven, said open space and said furnace, a recuperator receiving the waste gases from the furnace, a U-shaped air passage connected at both ends to said passage, and means for employing the preheated air from said recuperator to cause a circulation of the oven air through said passage, the air being withdrawn from the drying oven at one end of the passage and dried and then reintroduced into the drying oven at the other end of the passage.

4. In heat treatment apparatus, the combination of a drying chamber and a burning chamber arranged in series, said chambers being spaced apart by an interposed open space, independent conveying means contained in each of said chambers, and means for conveying the product from the drying chamber to the burning chamber.

5. In heat treatment apparatus, the combination of a plurality of pairs of chambers each comprising a drying chamber and a burning chamber, said chambers being spaced apart by an interposed open space, said pairs being in alignment and in spaced relation with each other, means for conveying the product in turn through said pairs of chambers and means for conveying the products over the intervening spaces between the chambers.

6. In heat treatment apparatus, the combination of a plurality of pairs of chambers each comprising a drying chamber and a burning chamber, said pairs being in alignment and in spaced relation with each other, independent conveying means contained in each of said chambers, and means for conveying the product from one pair of chambers to the next pair of chambers.

7. In heat treatment apparatus, the combination of a plurality of pairs of chambers each comprising a drying chamber and a

burning chamber, said chambers being spaced apart by interposed open spaces, and said pairs being in alinement and in spaced relation with each other, and a continuous conveyer floor extending through said chambers and said open spaces and comprising power driven rollers.

8. In heat treatment apparatus, the combination of a drying chamber and a burning chamber arranged in series, said chambers being spaced apart by an intervening open space, and a continuous conveyer floor extending through said chambers and said open space and comprising power driven rollers.

9. In enameling apparatus, the combination with a drying oven, a burning furnace, said drying oven and furnace being arranged for straight line operation, and a recuperator wherein air is heated by the waste gases from the furnace, of means for drying the atmosphere in the drying oven comprising means for withdrawing the air from said oven, heating said air and reintroducing said air into the oven.

10. In enameling apparatus, the combination with a drying oven, a burning furnace and a recuperator wherein air is heated by the waste gases from the furnace, of means for drying the atmosphere of said drying oven which consists of a passage having its ends connected to said furnace at points spaced longitudinally of the latter whereby a portion of the air may be by-passed through the passage, and a hot air inlet leading from the recuperator to said passage.

11. In enameling apparatus, the combination with a drying oven, a burning furnace and a recuperator wherein air is heated by the waste gases from the furnace, of means for drying the atmosphere of the drying oven which consists of a plurality of passages each having its ends connected to the drying oven at points spaced longitudinally of the drying oven whereby a portion of the air may be by-passed through the passage, and hot air inlets leading from the recuperator to said passages.

12. In heat-treatment apparatus, the combination of a heating chamber, an air circulating passage having an inlet portion and an outlet portion, both portions connected to said chamber, and means for causing circulation of the air of said chamber through said passage whereby to create regulable air currents in said chamber.

13. In heat-treatment apparatus, the combination of a heating chamber, an air circulating passage having an inlet portion and an outlet portion, both portions connected to said chamber, means for causing circulation of the air of said chamber through said passage whereby to create regulable air currents in said chamber, and means for reheating the air traveling through said passage.

14. In heat-treatment apparatus, the combination of a heating chamber, a plurality of air circulating passages each provided with an inlet portion and an outlet portion, both portions being connected to said chamber, and means for causing air from said chamber to circulate through said passages whereby to create regulable air currents in said chamber.

15. In heat-treatment apparatus, the combination of a heating chamber, a plurality of air circulating passages each provided with an inlet portion and an outlet portion, both portions being connected to said chamber, means for causing air from said chamber to circulate through said passages whereby to create regulable air currents in said chamber, and means for reheating the air traveling through said passages.

16. In heat-treatment apparatus, the combination of a heating chamber, means for causing the product to be treated to travel through said chamber, a plurality of air-circulating passages having their inlet and outlet ends connected to said chamber, and means comprising the introduction of heated air into said passages for causing a circulation of currents of air within said chamber and through said passages.

17. In heat-treatment apparatus, the combination of a heating chamber, means for causing the product to be treated to travel through said chamber, a plurality of air-circulating passages having their inlet and outlet ends connected to said chamber, said passages being positioned in spaced relation to each other longitudinally of said chamber, and means comprising the introduction of heated air into said passages whereby circulating currents of heated air are set up throughout said chamber whereby to maintain the desired heat exchange in said chamber.

Signed at Pittsburgh, Pa., this 21st day of December, 1927.
